UNITED STATES PATENT OFFICE

160,656

TEXTILE FABRIC

Norman R. Peterson, San Francisco, Calif.

Application April 26, 1948, Serial No. 145,970

Term of patent 7 years

(Cl. D92—1)

To all whom it may concern:

Be it known that I, Norman R. Peterson, a citizen of the United States, and a resident of the city and county of San Francisco, State of California, have invented a new, original, and ornamental Design for a Textile Fabric, of which the following is a specification, reference being had to the accompanying drawing, forming part thereof.

Referring to the drawing:

Fig. 1 is a plan view of a textile fabric, showing my new design. A design unit is outlined by broken lines and is repeated as indicated over the fabric.

Fig. 2 is a plan view on an enlarged scale of the design unit.

I claim:

The ornamental design for a textile fabric, as shown and described.

NORMAN R. PETERSON.
